UNITED STATES PATENT OFFICE.

HERMAN ADLER, OF NEW YORK, N. Y.

LOCK.

1,112,246.

Specification of Letters Patent. Patented Sept. 29, 1914.

Application filed December 23, 1913. Serial No. 808,361.

To all whom it may concern:

Be it known that I, HERMAN ADLER, a subject of the King of Roumania, and a resident of the city of New York, Richmond Hill, borough of Queens, in the county of Queens and State of New York, have invented a new and Improved Lock, of which the following is a full, clear, and exact description.

10 My invention has for its object to provide a lock particularly well adapted for use on elevator doors, the lock having a bolt with a threaded orifice in which meshes a threaded shaft connected with a cylinder or other locking means. A latch bar is provided for engagement by the bolt for locking the latch bar relatively to the bolt.

Still other objects of the invention will appear in the following specification in 20 which the preferred form of my invention is disclosed.

In the drawings similar reference characters refer to similar parts in all the views in which—

25 Figure 1 is a sectional plan view showing how my lock is used for securing an elevator door; Fig. 2 is a perspective plan view of the lock; and Fig. 3 is a sectional elevation showing the invention.

30 By referring to the drawings it will be seen that a casing 5 is provided, the casing 5 having an inner wall 6 to which the door of the casing is secured by means of screws 7 and flanges 8 extending from the top of 35 the casing. In the casing there is an opening 9 which extends through the top wall of the casing, there being also openings 10 which extends through the opposite side walls of the casing. These openings 9 and 40 10 are provided for receiving the end 11 of a bar 12, the bar 12 having a recess 13 for receiving the lug 14 with which the bolt 15 is provided. This lug 14 which is disposed adjacent the wall 16 of the casing 5 and 45 which has the opening 9, is disposed substantially parallel with the said wall 16 for moving into the recess 13 in the bar 12. The lug 14 which extends from the wall 17 of an opening 18 in the bolt 15 is spaced from the 50 opposite wall 19 of the opening. The lug 14 is also spaced from the inner end 20 of the opening. The bolt 15 and the lug 14 are constructed in this manner to permit the bar 12 to pass the lug 14 to a position where it

may be disposed between the lug 14 and the recess 20 of the opening 18 when the lug 14 is moved into the recess 13 of the bar 12.

As a means of moving the member 15 with this lug 14, I provide the bolt 15 with a threaded opening 21 in which is disposed a threaded member or shaft 22, this threaded member or shaft 22 being journaled in the bearings 23 and 24 in the casing 5. When the threaded member or shaft 22 is rotated, it will be understood that it will move the bolt 15 so that the lug 14 will be moved into or out of the recess 13 in the bar 12 as may be desired. The casing 5 is preferably secured to the inner side 24 of the door 25, and the inner end 26 of the threaded member or shaft 22 is provided with a slot 27 so that a key of any desired construction may engage the end 26 of the threaded member or shaft 22 at the slot 27 to rotate the threaded member or shaft 22 75 to operate the bolt as desired. When the lock is to be operated at the outer side of the door, I prefer to use a locking means such as cylindrical locking means 28 as shown in Fig. 3 of the drawings. This cylindrical locking means 28 is disposed in an opening 31 at the outer side 29 of the door 25 and is provided with flanges 30 for engaging the outer side 29 of the door 25. This cylindrical locking means may be of 80 any desired construction, the locking means being held in position by a threaded bolt 32 which is disposed in an opening 33 in a plate 34, at the inner side of the door, and which meshes in a threaded orifice 35 in the cylindrical locking means 28. The plate 34 has an offset portion 36 in which there is disposed an opening 37 for the rod 38 which has a flattened end 39 disposed in a recess 40 in the inner end of the threaded member or 90 shaft 22, the rod 38 being secured to the cylinder 41 of the cylindrical locking means 28 by means of an opening 42 and a cotter pin 43.

When the invention is used and there are 100 several elevator doors, the proprietor may lock all of the elevator doors but one by the insertion of a key in the slot 27 of the lock with which the doors are provided, these locks being constructed without the cylindrical locking means 28 and the rods 38. The remaining door 25 is provided with a lock constructed with the cylindrical lock-

ing means 28 and the rod 38, and this remaining door is locked at the outer side by means of the key 44.

Having thus described my invention, I 5 claim as new and desire to secure by Letters Patent:

1. In a lock, a bolt having a top and a front end with a recess extending through the top and the front end, a lug extending 10 from the top of the bolt into the recess in the direction of the front end of the bolt, the lug being spaced from the bottom of the recess and the front end of the bolt.

2. In a lock, a threaded bolt having a top 15 and a front end with a recess extending through the top and the front end, a lug extending from the top of the bolt into the recess in the direction of the front end of the bolt, the lug being spaced from the bottom of the recess and the front end of the bolt, a latch bar adapted to be disposed between the front end of the lug and the front end of the bolt, and having an opening for 20 receiving the lug, and a threaded member 25 meshing with the thread on the bolt for the purpose specified.

3. In a lock, a casing having an opening in its top, a bolt for moving horizontally in the casing and having a top and a front 30 end with a recess extending through the top and the front end, a lug extending from the top of the bolt in the recess in the direction of the front end of the bolt, the lug being spaced from the bottom of the recess and 35 the front end of the bolt, and a latch bar for insertion in the opening in the casing and in the recess in the bolt beyond the front of the lug to be retained by the lug when the bolt is moved into operative position.

4. In a lock, a casing, the casing being provided with an opening in its top, a bolt for moving horizontally in the casing and with a horizontally disposed threaded opening, the bolt having a top and a front end 40 with a recess extending through the top and the front end, a lug extending from the top 45

of the bolt into the recess in the direction of the front end of the bolt, the lug being spaced from the bottom of the recess and the front end of the bolt, a latch bar for insertion in the opening in the casing and in the recess in the bolt beyond the front of the lug to be retained by the lug when the bolt is moved into operative position, and a threaded member for meshing in the threaded opening in the bolt and journaled in bearings in the casing. 50 55

5. In a lock, a cylindrical locking means having a threaded orifice, and adapted to be inserted in an opening at one side of a door, 60 a plate adapted to be disposed at the other side of the door and having two openings, a screw member normally disposed in one of the openings and meshing in the threaded orifice, a casing normally secured against 65 the plate, the casing having an opening in its top, a bolt for moving horizontally in the casing, and with a horizontally disposed threaded opening, the bolt having a top and a front end, there being a recess in the bolt 70 extending through the top and the front end adjacent the opening in the casing, a lug extending from the bolt into the recess in the direction of the front end of the bolt, the lug being spaced from the bottom of the recess and the front end of the bolt, a latch bar for insertion in the opening in the casing and in the recess in the bolt to be retained by the lug when the bolt is moved 75 into operative position, a threaded member 80 meshing in the threaded opening in the bolt and journaled in bearings in the casing, and means connecting the cylindrical locking means with the threaded member. 85

In witness whereof I have signed my name 85 to this specification in the presence of the two subscribing witnesses.

HERMAN ADLER.
